DESIGN FOR A BEDSTEAD

Anthony J. Buckner, Jackson Heights, N. Y., assignor to Grosfeld House, Inc., New York, N. Y., a corporation of New York

Application July 23, 1942, Serial No. 107,653

Term of patent 3½ years

To all whom it may concern:

Be it known that I, Anthony J. Buckner, a citizen of the United States of America, residing in Jackson Heights, county of Queens, and State of New York, have invented a new, original, and ornamental Design for a Bedstead, of which the following is a specification, reference being had to the accompanying drawing, forming part thereof, wherein the figure is a perspective view of a bedstead, showing my new design, the sides being broken away for convenience of illustration.

I claim:

The ornamental design for a bedstead, substantially as shown and described.

ANTHONY J. BUCKNER.
